CLAMPING INSTRUMENT AND PROCESS OF
USING THE SAME

Henry D. Furniss, New York, N. Y.

Application December 29, 1933, Serial No. 704,455

13 Claims. (Cl. 128—346)

My invention relates to an instrument adapted to facilitate the making of closures or jointures, especially in operations upon the intestine, and the process of using the same.

5 The object of my invention is to provide an apparatus and process of using the same, whereby jointures or closures generally may be readily made and whereby especially operations upon the intestine may be carried out more expeditiously and with greater certainty and uniformity in results. A further object is to more effectively prevent the escape of any contents, as, for instance, intestinal contents and at the same time prevent bleeding during the operation. Further 10 objects of my invention will appear from the detailed description of the same hereinafter.

While my invention is capable of being carried out in many different ways, for the purpose of illustration I have shown only one embodiment of the apparatus involved therein, in the accompanying drawings, in which—

Fig. 1 is a side elevation of an apparatus;

Fig. 2 is a perspective view of the same;

Fig. 3 is a plan view of a portion of the gripping jaws, enlarged;

Fig. 4 is a perspective view of one set of gripping teeth;

Fig. 5 is a longitudinal section of a protector used on the end of the pin;

Fig. 6 is a diagrammatic section showing the way used for closing the end of the intestine;

Fig. 7 is a diagrammatic elevation showing the initial step of clamping two ends of intestines together where two ends are to be joined;

Fig. 8 is a similar view showing the way of sewing the two ends together;

Fig. 9 is a diagrammatic view showing the end of an intestine about to be joined to the side of an intestine;

Fig. 10 is an elevation showing the step of clamping the end to the side of the intestine; and

Fig. 11 shows them as finally joined together.

In the accompanying drawings, I have shown an operating instrument comprising a clamp-like apparatus which comprises two jaws 1 and 2, pivoted together by means of a pivot pin 3 and having handles 4 and 5, respectively, one of said handles 4, having a screw-threaded arm 6 secured in a slot 7 so as to be inserted and withdrawn from a slot 8 in the handle 5. A thumb-screw 9 on the arm 6 enables the clamping jaws to be tightly held together. The jaw 1 is provided with a sinuous jaw surface 10 to interfit with a similar surface 11 on the jaw 2, of such a shape that when

the intestine is inserted between the jaws there will be formed a channel 12 of approximately the width of the intestine clamped together throughout the length of the channel 12. In this way it will be noted that rounded teeth 13 and 14 are formed on the jaws 1 and 2, respectively, and that in said teeth 13 and 14 there are provided notches 15 which, in the clamping position of the instrument with the intestine clamped in place, that is to say, when the channel 12 is approximately of equal width throughout, there will be just sufficient room in the notches 15, between the teeth 13 and 14, to provide room for receiving a pin 16 having a knurled handle 17, on the end of which there is adapted to be placed a guard 18 to prevent the operator from being injured or becoming infected from the point of the pin 16. The guard 18 is comprised of a pear-shaped housing 19 having a tapered forward end 20 with an opening 21 to receive the end of the pin and a rearward opening 22 to receive a tubular plunger 23 which has longitudinal slits 24 at the forward end to provide clamping fingers 25 which become wedged around the pin near the opening 21 due to the tapered end of the housing 19. The plunger, 20 furthermore, has a shoulder 26 to receive a coil spring 27 which normally forces the plunger 23 towards the opening 21. The rear of the plunger has a knob 28 permitting the same to be withdrawn to release the pin and a closure 29 to prevent the point of the pin from projecting through the end of the plunger 23. It will be noted that the clamping jaws 1 and 2 are outwardly curved so as to permit the guard 18 to be placed over the end of the pin 16.

In carrying out my invention, it will be understood that the apparatus described may be used in joining portions of the intestine or other tissues, in many different ways. However, for example, it may be used particularly for closing the end of an intestine or joining two ends thereof together, or joining an end to a side of the intestine.

In the case where the end of the intestine is to be closed, the end of the intestine is inserted between the clamping jaws 1 and 2 and the jaws clamped together with the thumb-screw 9, after which the pin 16 is then inserted and the guard 18 is placed over the end of the same. The clamping device is then removed and the end of the intestine is then sewed together by cross-stitches 30 of catgut, so that the free ends of the intestine are then directed inwardly, as shown in Fig. 6. After the stitching is completed the pin 16 can be removed. If desired, an additional sewing 110

could be accomplished in this instance by, instead of using the pin 16, using a needle to which catgut is attached and which may be pulled through the intestine by the needle in the final 5 step of completing the operation.

Where two ends 31 and 32 of the intestine are to be attached together, these are first clamped between the clamping jaws 1 and 2, as shown in Fig. 7, the pin 16 is then inserted and the guard 10 18 applied thereto, whereupon the excess ends of the intestine are cut off, the clamp is removed and the intestine stitched all around the outside of the intestine, as shown in Fig. 8. Thereafter 15 the pin 16 is removed.

In the case where an end 33 of the intestine is to be attached to the side of an intestine 34, the procedure is similar to that where the two 20 ends of the intestine are to be joined together, in that the side 34 of the intestine is clamped between the jaws 1 and 2 together with the end 33 of the intestine. At this time a slice can be taken from the clamped fold of the side of the intestine. The clamp is then removed and the stitching with catgut is applied all around the adjacent 25 surfaces of the intestine 33 and the intestine 34, so that the joined end to side appear as in Fig. 11 after the pin 16 has been removed.

While I have described my invention above in detail I wish it to be understood that many 30 changes may be made without departing from the spirit of the same.

I claim:

1. A clamp having jaws with interprojecting teeth respectively and a longitudinal pin recess 35 formed in said teeth by grooves in the ends of the teeth facing towards the opposite jaws.

2. A clamp having jaws with interprojecting teeth respectively and a longitudinal pin recess 40 formed in said teeth, said jaws being provided with offset handles at one end and an offset pivot for the jaws at the other end so as to permit the ends of the pin to project from the jaws at both 45 ends of the pin.

3. The method which comprises clamping a thin material in a circuitous path, inserting a pin 45 into the circuitous path of the material through folds thereof, then removing the clamp and stitching the material while the pin remains in the latter.

4. The method which comprises clamping a thin material in a circuitous path, inserting a pin 50 into the circuitous path of the material within the clamp through folds thereof, then removing the clamp and stitching the material while the pin remains in the material.

5. The method which comprises clamping disconnected intestine portions in a circuitous path, inserting a pin into the circuitous path of the 55

material through folds thereof, then removing the clamp and stitching the material while the pin remains in the latter.

6. The method which comprises clamping disconnected intestine portions in a circuitous path, 80 inserting a pin into the circuitous path of the material within the clamp through folds thereof, then removing the clamp and stitching the material while the pin remains in the material.

7. The method which comprises clamping disconnected intestine portions in the form of two disconnected ends in a circuitous path, inserting a pin into the circuitous path of the material 85 through folds thereof, then removing the clamp and stitching the material while the pin remains in the latter.

8. The method which comprises clamping disconnected intestine portions in the form of two disconnected ends in a circuitous path, inserting a pin into the circuitous path of the material 90 within the clamp through folds thereof, then removing the clamp and stitching the material while the pin remains in the material.

9. The method which comprises clamping disconnected intestine portions in the form of an 100 end and a side portion, making a slice in the side portion, in a circuitous path, inserting a pin into the circuitous path of the material through folds thereof, then removing the clamp and stitching the material 105 while the pin remains in the latter.

10. The method which comprises clamping disconnected intestine portions in the form of an end and a side portion, making a slice in the side portion, in a circuitous path, inserting a pin into the circuitous path of the material within the 110 clamp through folds thereof, then removing the clamp and stitching the material while the pin remains in the material.

11. The method which comprises clamping a thin material in a circuitous path, inserting a 115 needle in a given direction into the circuitous path of the material through folds thereof from one side of the clamped material, drawing a stitching material after the needle in the same direction into the material within the clamp 120 through to the other side of the clamped material and then removing the clamp.

12. A clamp having interprojecting teeth respectively on jaws pivoted together at one end of the set of teeth, handles on the respective jaws 125 at the other end thereof, and a longitudinal pin recess formed in said teeth.

13. A clamp having interprojecting teeth respectively on jaws pivoted together at one end of the set of teeth, a handle thereon, and a longitudinal pin recess formed in said teeth.
